UNITED STATES PATENT OFFICE.

JOHN C. SINN, OF MCKEESPORT, PENNSYLVANIA.

DOOR-LOCK.

1,209,053.

Specification of Letters Patent. Patented Dec. 19, 1916.

Application filed March 28, 1916. Serial No. 87,304.

To all whom it may concern:

Be it known that I, JOHN C. SINN, a citizen of the United States, residing at McKeesport, in the county of Allegheny, State of Pennsylvania, have invented certain new and useful Improvements in Door-Locks; and I do hereby declare the following to be a full, clear, and exact description of the invention, such as will enable others skilled in the art to which it appertains to make and use the same.

This invention relates to door locks, and has for its primary object to provide simple and efficient means whereby a door may be securely locked from either the inside or outside of the door, and yet which may be unlocked from inside of the same upon actuation of the latch retracting knob.

A further object of the invention is to provide a device of this character which is of simple and inexpensive construction, the parts of which are all so arranged or assembled as to be positive in operation and yet proof against breakage, wear, or derangement of the same, and which will prove thoroughly efficient in the attainment of the ends for which it is designed.

With these objects in view, together with others which will appear as the description proceeds, the invention resides in the novel combination and arrangement of parts, all as will be described more fully hereinafter, illustrated in the drawings, and particularly pointed out in the claims.

The invention will be best understood by reference to the accompanying drawings, wherein:

Figure 1, is a vertical sectional view taken through a lock embodying my invention, the said view being taken from the inside of the door and illustrating the lock bolt in locked position, Fig. 2, is a similar view showing the lock bolt retracted by operation of the latch stem, Fig. 3, is a sectional view taken on line 3-3 of Fig. 1, and Fig. 4, is a sectional view on line 4-4 of Fig. 1.

Referring now more particularly to the drawings, the lock casing is indicated at 5. This casing is of preferably shallow construction, and is closed at one side by the removable plate 6; the said casing being adapted for insertion within the free edge of a door.

The latch bolt comprises an elongated shank 7, the same being mounted for sliding movement within the lock casing, and is sup-

ported therein by a pin or stud 8, the said stud projecting from one of the inner walls of the casing through an elongated slot 9 in the latch shank, a coil spring 10 being arranged in the said slot to abut at one end with the stud 8 and at its opposite end with the end wall of the slot. This construction obviously maintains the latch bolt normally in extended or latching position. The innermost end of the latch shank is widened and apertured as at 11 to permit of the latch actuating knob stem extending therethrough, and the extremity of the said widened portion provides a laterally extending flange 12 to be engaged by the knob lugs to retract the latch.

Mounted within the casing beneath the latch shank and in parallel relation thereto is a sliding lock bolt 12, the said bolt being supported by the bracket lugs 14 within the casing, and is yieldably held in either extended or retracted position by the spring 15, the latter being secured at one end to the lock casing and engaging the stud 16 at its free end. The lower edge of the lock bolt at the innermost end of the latter is notched as at 17 to permit of the engagement with a key detent inserted through the key hole 18 of the casing or plate to extend or retract the lock bolt as desired. Lugs 19 project inwardly from the side of the casing upon each side of the key hole 18, the innermost faces of the said lugs being serrated or notched as at 20 to enable the notched edge 85 of the key detent freely passing by the lugs, but to prevent the use of unauthorized keys for retracting the lock bolt. Projecting laterally from the upper edge of the lock bolt adjacent the rear end of the latter is a shoulder 21, the said shoulder extending preferably the entire depth of the casing.

The latch actuating knobs are indicated at 22 and 23, the former being the knob extending to the outside of the door, while the latter projects inwardly from the door. These knobs are provided with the usual stems 24, angular in cross section, one of the said stems being provided at its inner extremity with a socket or recess 25 for the accommodation of a reduced projection 26 upon the extremity of the opposite stem, the stems thus arranged being extended through the apertured end of the latch shank and forming a continuous latch actuating bar 105 disposed transversely of the lock casing.

It will be observed that the particular con-

struction permits of the rotation of one of the door knobs without effecting the movement of the other. Secured upon each of the latch actuating stems and in close proximity to each other are the latch retracting lugs 27 and 28 respectively, the said lugs being adapted upon the rotation of their respective stems to engage with the flange 12 at the latch end to retract the said latch against the tension of the spring 10. A bolt retracting arm 29 may be formed upon the stem of the knob 23, or may be a part of the lug 28, the said arm projecting downwardly from its stem to engage with the shoulder 21 upon the bolt. From this construction it is apparent that the rotation of the outside knob 22 will retract the latch shank 7, but can in no way effect the sliding movement of the lock bolt 12. When the bolt 12 has been projected by the use of a key inserted through the opening 18, rotation of the inner knob 23 will cause the arm 29 carried thereby to engage the shoulder 21 and retract the bolt 12. When fully retracted, the bolt will be so held by the spring 15. By this construction, the door may be securely locked from either side, and held against unlocking movement through any rotation of the outer knob, but which will be instantly unlocked upon rotary movement being applied to the inner knob 23. Locks of this character are adapted specially for use upon doors of school houses, public buildings, and other such places wherein it may be found necessary to quickly open the exit, it being readily seen that the insertion of a key will not be necessary to unlock the door from the inside.

While I have herein shown and described a particular or preferred embodiment of the

invention, various changes may be made in the minor details of construction without departing from the spirit of the invention or exceeding the scope of the claims.

What is claimed is:

1. In a lock of the class described, a latch, a pair of latch actuating stems, one of said stems being provided in its end with a recess, a projection on the other of said stems for engagement in said recess, a flange on said latch, lugs carried by each of said stems for engagement with said flange, a lock bolt, a shoulder on said lock bolt, and an arm on one of said lugs adapted to engage said shoulder, substantially as described.
2. In a lock of the class described, a casing, latch stems projecting from said casing and being mounted for rotation independently of each other, a latch mounted for sliding movement in said casing, one of said latch members being enlarged and apertured for inclosing said stems, a flange projecting laterally from said widened portion, latch actuating lugs on said stems adapted to engage said flange, a lock bolt mounted for sliding movement in said casing, a shoulder on said bolt, an arm on one of said lugs adapted to engage said shoulder, means for locking said bolt, means for yieldably holding said latch projected, and means for yieldably supporting said lock bolt in extended or retracted position, substantially as described.

In testimony whereof, I affix my signature, in the presence of two witnesses.

JOHN C. SINN.
